HOLDER FOR MAGAZINE TYPE RAZORS

George Douglas Jones and Leonidas C. Miller,
Los Angeles, Calif., assignors to Reelshav Corporation,
Los Angeles, Calif., a corporation of California

Application June 6, 1949, Serial No. 97,338

12 Claims. (Cl. 30—40)

1

This invention relates to safety razors and is particularly directed toward a novel form employing a sharpened ribbon blade of considerable length which may be unspooled from a magazine to present successive unused portions as desired.

This application is a continuation-in-part of our copending application, filed June 19, 1948, for "Magazine Type Razor," now Patent No. 2,492,292, issued December 27, 1949, and constitutes an improvement over the copending applications of George Douglas Jones for "Razor," filed July 6, 1948, now Patent No. 2,492,293, issued December 27, 1949, and for "Ribbon Type Razor Assembly," filed April 28, 1949, Serial No. 90,059.

The principal object of this invention is to provide a new and improved form of shaving razor.

Another object is to provide a novel form of holder for a disposable blade magazine.

Another object is to provide a holder for a blade magazine, the holder including a head inclined forwardly from a supporting upright handle, and a guard pivotally associated with the head and cooperating therewith to define a magazine-receiving pocket.

Another object is to provide a holder of this type in which the pivotal mounting of the guard on the razor head is such as to permit universal swiveling movement of the guard, as well as limited longitudinal movement, in order that the blade magazine may be aligned and maintained in operative position by means of a transverse lip provided on the head.

Another object is to provide a holder of this type having novel means for clamping the pivoted guard in operative position.

A further object is to provide a shaving razor utilizing a ribbon blade and constructed in a manner so that the sharpened edge of the blade is kept out of contact with parts of the razor in order to maintain maximum sharpness.

Other and more detailed objects and advantages will appear hereinafter.

In the drawings:

Figure 1 is a front elevation of a preferred embodiment of our invention.

Figure 2 is a side elevation thereof.

Figure 3 is a sectional elevation taken substantially on the lines 3—3 as shown in Figure 1, the blade magazine being unsectioned.

Figure 4 is a perspective view of a preferred form of blade magazine and showing a knob for advancing a continuous ribbon blade, whereby an unused portion is presented for shaving.

2

Figure 5 is a rear elevation of the magazine.

Figure 6 is a sectional plan view on an enlarged scale partly in section of the magazine taken substantially on the lines 6—6 as shown in Figure 5.

Figure 7 is a front elevation of the magazine partly in section taken substantially on the lines 7—7 as shown in Figure 6.

Figure 8 is a sectional plan view taken substantially on the lines 8—8 as shown in Figure 7.

Figure 9 is an enlarged sectional elevation of the magazine and holder taken substantially on the lines 9—9 as shown in Figure 7.

Figure 10 is a view similar to Figure 9 taken on the lines 10—10 as shown in Figure 7.

Figure 11 is a sectional detail taken substantially on the lines 11—11 as shown in Figure 7.

Figure 12 is a sectional detail on an enlarged scale taken substantially on the lines 12—12 as shown in Figure 5.

Referring to the drawings, the holder generally designated 10 includes a head 11 and a guard member 12 secured together by means of a pivotal connection designated 13. A magazine 14 is received within a pocket 15 defined by the head 11 and guard 12, and this magazine carries a flexible ribbon blade 16 of considerable length. One edge of the blade is sharpened as indicated at 17. The head 11 inclines forwardly at an acute angle from its vertical neck portion 8 and is secured by means of a suitable connection 18 to the vertically extending handle 19.

The magazine 14 is generally rectangular in shape and is relatively thin compared to its length and width. The lower edges of the rectangle may be rounded as indicated in the drawings. The magazine may include a base 20 and a cover 21 secured by any convenient means such as, for example, by means of projecting pin elements 22 on the base 20 which extend through apertures 23 in the cover 21 and which are later deformed as indicated at 24 to prevent disassembly (see Figure 10).

A horizontal slot 25 provided in the base 20 separates the main portion of the base 20 from the horizontal bridge 26. A slot 27 in the cover 21 is aligned with the base slot 25, and a forwardly extending flange 28 on the cover 21 overlies the bridge 26. The ribbon blade 16 extends across the upper surface 29 of the bridge 26 and under the flange 28. The ribbon blade 16 extends from a supply coil 30 positioned within a recess 31 provided in the base 20. The other end of the blade 16 may be received in a mounting slot 32 provided in a take-up drum or spool 33 positioned

within the recess 34. The recess 34 is also formed in the base 20 and is positioned symmetrically with the recess 31 with respect to the bridge 26.

A noncircular opening 35 is provided in the reel 33, and a cooperating noncircular projection 36 on the knob 37 is carried on the head 11 and projects through an aperture 38 provided therein. A flange 39 on the knob 37 prevents disassembly with respect to the head 11. The size of the aperture 38 is somewhat larger than the hub 40. The reel 33 is provided with outwardly extending hub portions 62 which are received within the axially aligned openings 63 and 64 provided in the base 20 and cover 21 respectively. It will be recognized that the knob 37 need not be attached to the head 11 but may comprise a separate and distinct part if desired, and indeed may be shaped to be received within a convenient recess provided on the handle 19. Rotation of the knob 37 serves to wind the ribbon blade 16 onto the reel 33 and hence cause the blade to move across the bridge 26 and unspool from the reel 30.

Rounded surfaces 42 and 43 are provided on the base 20 and are contacted by the ribbon blade 16 at each end of the bridge 26. Guide flanges 44 and 45 extend along the sides of the curved surfaces 42 and 43 respectively, and these guide flanges are positioned adjacent the sharpened edge 17 of the ribbon blade 16. As shown in Figure 4, the guide flanges merge at their lower ends into the end walls 46 of the base 20 and terminate at their upper ends near the intersections of the curved surfaces 42 and 43 with the upper plane surface 29 of the bridge 26. The sharpened edge 17 of the blade is kept away from contact with the flanges 44 and 45 in order to maintain the blade at its maximum sharpness and to avoid the possibility of dulling before use.

Means are provided for maintaining the heel edge 47 against the inner surface 48 of the cover 21, and as shown in the drawings, this means includes the slanting of the surfaces of the curved ends 42 and 43 so that the heel end 47 of the blade 16 travels over a shorter arc than the portion of the blade adjacent the sharpened edge 17, as is clearly shown in Figure 11. Thus, tensioning of the ribbon blade 16 between the substantially conically curved portions 42 and 43 causes the blade to move toward the "low side" and thereby move the heel 47 against the surface 48.

As a further aid in positioning the sharpened edge 17 so that it will not be contacted prior to use during shaving, and in this way to insure its maximum sharpness, the recess 31 is provided with a tapering wall 49 which is larger on the diameter adjacent the cover 21 than on the inner diameter at the bottom of the recess. The angle of inclination of the wall 49 and the inclination of the curved surface 42 have each been exaggerated in Figures 9 and 11 of the drawings for clarity of illustration. The effect of this tapered bore is to cause the individual loops of the coil to expand to the largest diameter and hence move the heel edge 47 of the continuous ribbon blade 16 into contact with the cover 21. The sharpened edge 17 is in this way held out of contact with the bottom 50 of the recess 31. An annular nonmetallic washer 51 may be mounted in the bottom of the recess 31 if desired as a further protection for the sharpened edge 17, and this washer 51 may have a central aperture to receive the centering boss 52 (see Figure 7). The cover may comprise a metal stamping, if desired, and be provided with a pair of annular ridges 53 to

secure additional stiffness. Recesses 65 in the head 11 afford clearance for the annular ridges 53.

Ratchet means are provided to prevent unspooling of the drum 33 and thereby maintain tension on the ribbon blade 16. As shown in the drawings, this means includes a plurality of ratchet teeth 54 formed on the side face of the reel 33, together with a pawl element 55 for engaging the teeth 54. This pawl element 55 may be formed as an integral part of the cover 21 and may be separated by a stamping operation from the remainder of the cover along the radial line 56 and intersecting circumferential line 57. The pawl 55 is deformed inwardly as shown in Figure 12, and its integral connection with the cover 21 provides sufficient resilience to permit the pawl to deflect outwardly and allow the ratchet teeth 54 to pass by in one direction. Reverse rotation of the reel 33 is prevented. From this description it will be observed that a ratchet and pawl device has been provided for preventing a reverse rotation of the reel 33, which device requires no separate or additional parts and which may be manufactured economically on a quantity basis.

The tendency of the coil loops to expand within the recess 31, together with the friction of the blade 16 over the curved surface 42, provides sufficient frictional resistance to maintain proper tension on the blade as it reaches the bridge 26. The ratchet device 54, 55 prevents unwinding of the blade at the other end of the bridge.

The ribbon blade 16 extends from the coil 30 through a slot 58 leading from the recess 31 to the curved surface 42, the outer end of the slot being defined by the upper edge 59 of the end wall 46. A similar slot 60 is provided on the other side of the base communicating with the recess 34. Nonmetallic sealing elements 61 may be provided adjacent the slots 58 and 60 in a position to contact the ribbon blade 16. These sealing elements 61 assist in excluding entrance of water or foreign matter into the recesses 31 and 34.

Means are provided for maintaining the pivoted guard member in closed position and for urging the magazine 14 into engagement under the lip 66 provided on the head 11. As shown in the drawings, this means includes a cam member 67 pivotally mounted with respect to the handle 19 and head 11 by means of the pin 68. The nose 69 of the cam is adapted to abut the lower end 70 of the guard 12. A slot 71 in the head 11 loosely receives the tab 9 so that the guard may have limited universal swiveling movement and may also move longitudinally in a direction parallel to the head 11. The shelf 72 on the guard 12 supports the magazine 14 along its lower edge so that upward movement of the guard 12 serves to clamp the magazine 14 between the lip 66 and shelf 72. Since the cover or guard 12 is free to swivel with respect to the head 11, the magazine 14 is aligned by the lip 66 and not by the shelf 72. This clamping action serves to hold the magazine 14 securely in place and further acts to provide additional stiffness for the flange 28 which overlies the ribbon blade 16. Under this clamping force the flange 28 deflects slightly so that the ribbon blade 16 is held tightly on the bridge seat 29. The upper edge of the guard 12 is provided with the usual comb teeth 73. As shown clearly in Figures 9 and 10, the bridge 26 is cut away on its under side to provide an entrance opening 14 leading into communication

with the horizontal aligned slots 25, 27 and 75 provided in the base 20, cover 21 and head 11 respectively.

The cam 67 may be rotated to an inoperative position as shown by the dotted lines in Figure 1 to permit the guard 12 to be swung to open position as indicated by the dotted lines in Figure 2. The magazine 14 may then be installed by placing its lower edge on the shelf 72 and then swinging the guard 12 toward closed position so that the magazine 14 remains in the pocket 15. As the guard is swung toward closed position the noncircular projection 36 enters the noncircular opening 35 in the take-up spool or reel 33. The relatively loose fit of the knob member 37 in the head opening 38 facilitates this operation.

The flange 28 on the magazine cover 21 underlies the lip 66 on the head 11. The cam 67 is swung to its operative position so that the nose 69 engages the lower edge 70 of the guard 12 and moves the guard and magazine upwardly to clamp the magazine between the lip 66 and shelf 72. The razor is then ready for use.

When the exposed or active portion of the sharpened edge 17 becomes dulled through use, the knob 37 is rotated to bring a fresh portion into position on the bridge 26. A very large number of active lengths are thus provided on the relatively long ribbon 16. When the blade 16 has been completely used up, that is, wound on the take-up reel 33, the holder 10 is opened and the used magazine 14 withdrawn. A new magazine is then inserted into the pocket 15 and the device is again ready for use. The new magazine may be handled without using great care since the cutting edge 17 is well guarded and shielded against contact, except for the exposed or active length extending along the bridge 26 between the flanges 44 and 45. If desired, a portion of the blade 16 which is initially exposed may have its cutting edge 17 dulled to further insure against accidental injury when installing the magazine 14 into the holder 10. The magazine 14 is automatically self-aligned on the razor head 11 by reason of its linear contact with the underside of the lip 66 and the point contact of the supporting guard 12 and swinging cam 67. When once installed the knob 37 is turned to bring the sharpened portion of the blade into operative position.

Having fully described our invention, it is to be understood that we do not wish to be limited to the details herein set forth, but our invention is of the full scope of the appended claims.

We claim:

1. A holder for a safety razor magazine, comprising in combination a head member having a forwardly extending lip along its upper edge, a handle member supporting the head member, a guard mounted on the head member and cooperating therewith to define a pocket for a magazine, pivot means for connecting the guard to the head member, said pivot means permitting limited translatory movement of the guard toward and away from said lip, and a movable element on one of the members adapted to engage the guard to swing it in a direction to close the pocket and to move the guard toward said lip.

2. A holder for a safety razor magazine, comprising in combination a head having a forwardly extending lip along its upper edge, a handle supporting the head, a guard member having comb teeth along its upper edge, pivot means for mounting the guard member on the head, said pivot means permitting limited translatory move-

ment of the guard member toward and away from said lip, the guard and head cooperating to provide a mount for a safety razor magazine, and a swinging element pivotally mounted on the head and adapted to engage the guard member and to move it toward said lip.

3. A holder for a safety razor magazine, comprising in combination a head member having a forwardly extending lip along its upper edge, a handle member supporting the head member, a guard mounted on the head member and cooperating therewith to define a pocket for a magazine, pivot means for connecting the guard to the head member, said pivot means including loose-fitting interengaging parts permitting limited swiveling and translatory movement of the guard relative to said head member, and a movable element on one of the members adapted to engage the guard to swing it in a direction to close the pocket and to move the guard toward said lip.

4. A holder for a safety razor magazine, comprising in combination a head having a forwardly extending lip along its upper edge, a handle supporting the head, a guard, pivot means for connecting the guard to the head, said pivot means permitting limited translatory movement of the guard toward and away from said lip and permitting swiveling movement of the guard, the guard and head cooperating to provide a mount for a safety razor magazine, and a movable element on the head adapted to engage the guard to swing it in a direction toward the head and to move the guard toward said lip.

5. A holder for a safety razor magazine, comprising in combination a head having a forwardly extending lip along its upper edge, a handle supporting the head, a guard, the guard having a shelf for supporting a razor magazine, pivot means for connecting the guard to the head, said pivot means permitting limited translatory movement of the guard toward and away from said lip and permitting swiveling movement of the guard, and a movable element on the head adapted to engage the guard to swing it in a direction toward the head and to move the guard toward said lip.

6. A holder for a safety razor magazine, comprising in combination a head having an abutment for engagement with an interfitting part on the razor magazine, a handle supporting the head, a guard having a shelf element for supporting the razor magazine, pivot means for connecting the guard to the head, said pivot means permitting limited translatory movement of the guard toward and away from said abutment, and a movable element on the head adapted to engage the guard and to move it in a direction toward said abutment.

7. A holder for a safety razor magazine, comprising in combination an inclined head having a forwardly extending lip along its upper edge, the head also having an upright supporting neck, a handle supporting the neck portion of the head, a guard mounted on the inclined head and cooperating therewith to define a pocket for the magazine, pivot means for connecting the guard to the head, said pivot means permitting limited translatory movement of the guard toward and away from said lip, and a movable cam element pivoted on the upright neck portion of the head and adapted to engage the guard to swing it in a direction to close the pocket and to move the guard toward said lip.

8. A holder for a safety razor magazine, comprising in combination an inclined head having a

7
forwardly extending lip along its upper edge and having an upright neck portion, a guard having a shelf for supporting a razor magazine, pivot means for connecting the guard to the head, said pivot means permitting limited translatory movement of the guard toward and away from said lip, and a movable element on the upright neck portion and adapted to engage the guard and to move it in a direction to engage the magazine under said lip.

9. A holder for a safety razor magazine, comprising in combination an inclined head having an abutment for engagement with an interfitting part on the razor magazine, the head having an upright neck portion, a guard having a shelf element for supporting a razor magazine, pivot means for connecting the guard to the head, said pivot means permitting limited translatory movement of the guard toward and away from said abutment, and permitting swiveling movement of the guard, an element pivoted on the upright neck portion of the head and adapted to engage the guard to move it in a direction toward said abutment.

10. In a safety razor, the combination of: a head having a forwardly extending lip, a disposable magazine adapted to be removably mounted on the head, the magazine having a cavity for a ribbon blade and provided with a transversely extending and continuous blade-contacting flange, and means adapted to maintain the magazine in operative position on the head and with said flange in self-aligning linear engagement under the lip, said means including a member engaging the magazine and having a tab loosely received within a slot provided on the head to permit swiveling movement of the member relative to the head.

11. In a safety razor, the combination of a head member having a forwardly extending lip along one edge, a guard member mounted on the head member and cooperating therewith to de-

5 fine a pocket, pivotal means connecting the guard member to the head member, said pivotal means including a tab on one member loosely received in a slot provided on the other member to permit swiveling movement between the members, a removable magazine adapted to be received in the pocket, said magazine having a cavity for a ribbon blade coil and provided with a transversely extending and continuous blade-contacting flange, clamping means including a movable element adapted to contact the guard member to maintain the magazine in operable position in said pocket with said flange in linear self-aligning engagement under the lip.

15 12. In a safety razor, the combination of a head having a forwardly extending lip along one edge, a handle adapted to support the head, a guard cooperating with the head to define a pocket, swivel means mounting the guard on the head including a tab on the guard loosely received within a slot provided on the head, a removable magazine member adapted to be received in the pocket, a member having a cavity for a ribbon blade coil and provided with a blade-contacting flange, clamping means for maintaining the magazine member in operative position, said means including a movable element on the head adapted to engage the guard in point contact to move the magazine member in a direction to bring said flange into linear self-aligning engagement under said lip.
